UNITED STATES PATENT OFFICE

EDGAR W. VAHLE, OF DAYTON, OHIO, ASSIGNOR TO THE HUFFMAN MANUFACTURING COMPANY, OF DAYTON, OHIO, A CORPORATION OF OHIO

LIQUID DISPENSING APPARATUS

Application filed April 14, 1930. Serial No. 444,207.

This invention relates to a liquid dispensing apparatus and more particularly to a device for refilling storage batteries with distilled water. One type of apparatus hereinbefore employed for that purpose comprises an ordinary jug supported in an inverted position in a carrying frame and provided in its mouth with a stopper which carries a discharge tube and a vent tube. While these devices have been used rather extensively they have not been wholly satisfactory for several reasons. A device of this kind must be of inexpensive construction and of light weight and it has been found difficult to provide such a device with satisfactory means for retaining the jug or container in a fixed position with relation to the frame. A friction clamp has been employed for this purpose, but the apparatus is subject more or less to rough use and the jars to which it is subjected cause the container to move downwardly, thus displacing it with relation to the other parts of the mechanism and sometimes causing the tube to come in contact with the floor and to be broken or injured. Further, the jars to which the apparatus is subjected, coupled with the weight of the water in the container, tend to loosen and displace the stopper. One object of the invention is to provide a dispensing apparatus of this character which will be simple in construction, efficient in its operation and in which the several parts will be positively retained in their proper positions.

A further object of the invention is to provide such an apparatus in which the container will be so secured to the frame that it will be retained therein when the frame is in either its normal upright position or in an inverted position and will be positively held against downward movement with relation to the frame when the frame is in its normal upright position.

A further object of the invention is to provide such an apparatus with means for positively retaining the stopper within the mouth of the container.

Other objects of the invention will appear as the apparatus is described in detail.

In the accompanying drawing Fig. 1 is a side elevation of a dispensing apparatus embodying my invention; Fig. 2 is a top plan view of the same; Fig. 3 is a bottom plan view of the apparatus; and Fig. 4 is a sectional view taken on the line 4-4 of Fig. 1.

In these drawings I have illustrated one embodiment of my invention but it will be understood that this embodiment has been chosen for the purposes of illustration only and that the apparatus may take various forms without departing from the spirit of the invention.

In that form here illustrated the apparatus comprises a frame consisting of upright side members 5 connected one with the other by annular frame members or bands 6, 7 and 8. The frame may have any suitable number of upright members and any suitable number of bands but the arrangement here shown has proven satisfactory. This frame is of such a character that it is adapted to receive and support a container for the liquid to be dispensed, such as an ordinary jug 9, which is preferably of glass and has at one end the usual centrally arranged discharge spout or mouth 10. Extending laterally from the spout is a handle or finger ring 11. The discharge spout or mouth of the jug is closed by a stopper 12 which is preferably of resilient material, such as rubber or cork. This stopper is provided with an outlet opening in which is mounted a discharge tube comprising a rigid inner portion 13 and a flexible outer portion 14. The stopper also carries a vent tube 15 which extends to a point near the bottom of the jug so that when the jug is inverted the open end of the vent tube will be above the level of the liquid.

The jug or container is mounted in the frame in an inverted position, that is, with the discharge mouth directed downwardly, and means are provided for retaining the same within the frame when the latter stands on either end. In the present construction, the upper annular band 6 is in the form of a split ring having at its end apertured ears 16 to receive a clamping bolt 100

17. This split ring fits about the bottom of the jug and is of such a width that it may be tightly clamped about the jug and project some distance beyond the bottom of 5 the jug, so that when the frame is inverted, and rests upon what is normally its upper end, the band 6 will engage the floor and the container or jug will be supported out of contact with the floor. The frame is provided 10 at its upper end with a handle or bail 18 by means of which it may be carried from place to place.

Near its lower end the frame is provided with a supporting member adapted to engage 15 beneath a portion of the container and positively hold the same against downward movement with relation to the frame. As here shown, this member is in the form of a bar 19 rigidly secured at its ends to the 20 vertical side members 5 of the frame. The transverse portion of the bar is arranged edgewise and is offset so that it will be out of line with the mouth of the container and will engage the laterally extending handle or 25 apertured part 11, thus causing the weight of the container to rest upon this bar. The bar is preferably arranged just above the lower annular band 8 so that the mouth of the 30 container will be supported slightly above that band and the discharge tube will be spaced such a distance from the lower edge of the band that there will be no likelihood of it coming in contact with the floor or other surface, on which the frame 35 may be set.

Movably mounted on the lower portion of the frame is a retaining member adapted to be extended beneath the stopper 12 and to retain that stopper in the mouth of the 40 container. As here shown, this retaining member is in the form of a rod 20 which is slidably supported in openings in the opposite sides of the frame, these openings being preferably formed in the vertical side members 5. The openings are so arranged with 45 relation to the transverse supporting bar 19 that when the rod is seated in both openings it will extend across and engage the outer end of the stopper. Preferably the openings are in a plane slightly above the normal position of the outer end of the stopper and when the retaining rod is placed in position the resilient material of the stopper will yield and the rod will therefore cause a constant inward pressure to be exerted on the 50 stopper. If the material of the stopper does not yield sufficiently to enable the rod to be placed in position the rod itself, being of metal, will yield and will thus exert pressure 55 on the stopper. Preferably the rod is provided at one end with a finger piece 21 by means of which it may be manipulated and it will be obvious that by withdrawing the 60 rod from the opening in that side of the frame opposite the finger piece 21 the rod

will be released and may be moved out of the path of the stopper. When the rod is to be replaced it is inserted across the end of the stopper and the free end thereof 70 pressed into line with the opening and the rod then moved lengthwise into the opening. If desired, the rod may be provided with one or more lugs 22 to prevent it from being entirely withdrawn from the frame.

The container or jug 9 is inserted in the frame in an inverted position while it is empty and the part 11 thereof caused to engage the supporting bar 19. The upper band 6 is then clamped about the jug to frictionally retain the same in position. The frame is then inverted so as to support the jug in an upright position, in which position it is filled and the stopper inserted and secured in position by the retaining rod 20. The flexible discharge tube 14 is carried beyond the side of the frame and toward the then lower part of the frame where it is inserted through an apertured lug or retaining ring 23 which retains the end of the tube 90 near the bottom of the jug so that when the frame is again placed in its normal upright position, with the jug inverted, the end of the tube will be above the level of the liquid in the jug and will thus prevent the discharge of liquid therefrom. It will be apparent that the construction is very simple but is of a strong durable character and is so arranged that it will not only support the parts positively in their proper positions but will protect the jug against injury when the frame is in either an upright position or in an inverted position. If desired, the frame may also be provided with a clip 24 to receive and support a hydrometer 95.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In a liquid dispensing apparatus, a container having a discharge spout and a part extending laterally from said spout, a stopper for said spout having an opening therethrough, a tube leading from said opening, a frame to receive said container and support the same with said spout directed downwardly and having means to retain said container therein, a member secured to said frame and arranged to engage said part of said container and positively hold said container against downward movement with relation to said frame, and a second member movably supported on said frame and arranged to engage said stopper when said part of said container is in engagement with 115

the first mentioned member and retain said stopper in said spout.

2. In a liquid dispensing apparatus, a container having a discharge opening at one end thereof, a stopper for said opening, a frame to support said container with said opening directed downwardly and having means to retain said container in a fixed position thereon, and a retaining member movably mounted on the lower portion of said frame and arranged to engage said stopper and retain the same in said opening.

3. In a liquid dispensing apparatus, a container having a discharge opening at one end thereof, a stopper for said opening, a frame to receive said container and support the same in a fixed position with said opening directed downwardly, and a retaining member to engage the outer end of said stopper and so connected with said frame that it will exert inward pressure on said stopper.

4. In a liquid dispensing apparatus, a container having a discharge opening at one end thereof, a stopper for said opening, a frame to receive said container and support the same in a fixed position with said opening directed downwardly, and a rod extending across the outer end of said stopper and having its ends connected with said frame in such relation to said stopper that said rod will exert inward pressure on said stopper.

5. In a liquid dispensing apparatus, a frame comprising upright members, and annular bands connecting said upright members, said frame being adapted to receive a jug and support the same in an inverted position and having means to retain said jug in a fixed position with relation thereto, said frame having openings in opposite sides thereof adjacent to the plane of the mouth of said jug, and a rod slidably mounted in said openings and arranged to extend across the mouth of said jug.

45 6. In a liquid dispensing apparatus, a frame comprising upright members, and annular bands connected with said upright members, said frame being adapted to receive a jug and support the same in an inverted position and having means to retain said jug therein, a bar rigidly secured to said frame and arranged to engage a part of said jug and hold the latter against downward movement with relation to said frame, and a rod movably mounted on said frame and arranged to extend across said frame beneath and adjacent to the mouth of said jug.

60 7. In a liquid dispensing apparatus, a container having an opening at one end thereof and a stopper for said opening, a frame to receive said container and support the same with said opening directed downwardly, said frame having means to retain said container therein, a bar rigidly secured

to said frame and arranged to engage a part of said container and hold the latter against downward movement with relation to said frame, and a rod movably mounted on said frame and normally so arranged with relation to said bar that it will engage said stopper and exert inward pressure thereon when said part of said container is in engagement with said bar.

75 8. In a portable liquid dispensing apparatus, a container having a discharge opening at one end thereof, and means for controlling the discharge of liquid through said opening, a frame to receive said container, said frame being adapted to be supported in an upright position with either end thereof resting on the floor and having at one end means to support the bottom of said container out of engagement with the floor when said frame is in a position to support said container with said discharge opening uppermost, and a bar supported at its ends by said frame near the other end of said frame and extending across said frame to hold said container against downward movement when said frame is inverted to support said container with said discharge opening directed downwardly.

90 9. In a portable liquid dispensing apparatus, a container having a discharge opening at one end thereof, a stopper inserted in said discharge opening, a discharge tube carried by said stopper and communicating with the interior of said container, a frame to receive said container, said frame being adapted to be supported in an upright position with either end thereof resting on the floor and having at one end means to support the bottom of said container out of engagement with the floor when said frame is in a position to support said container with said discharge opening uppermost, and a member supported at its ends by said frame near the other end thereof and engaging said stopper to retain the same in said discharge opening when said frame is inverted to support said container with said discharge opening directed downwardly.

95 10. In a liquid dispensing apparatus, a frame adapted to be supported on the floor with either end uppermost and comprising upright members and an annular band connected with said upright members, said frame being adapted to receive a jug and having means to retain said jug in a fixed position with relation thereto, and a retaining member mounted on said frame for movement into and out of a position in which it will extend across and adjacent to the mouth of said jug.

110 11. In a portable liquid dispensing apparatus, a container having a discharge spout, a frame adapted to be supported on the floor with either end uppermost and to receive said container through one end there-

of and support the same with said spout directed either upwardly or downwardly, a transverse member supported at its ends by said frame and arranged normally beneath and in the path of a part of said container to positively hold said container against downward movement with relation to said frame when said container is positioned with its spout directed downwardly,
10 said member being movable into and out of the path of said part while said container is supported in said frame.

12. In a portable liquid dispensing apparatus, a container having a discharge spout, a frame adapted to be supported on a floor with either end uppermost and to receive said container through one end thereof and support the same with said spout directed either downwardly or upwardly, an
15 elongated member engaging the opposite sides of said frame near the other end thereof, arranged normally in the path of said container and adapted to positively hold said container against downward movement
20 with relation to said frame when said spout is directed downwardly, said member being mounted for lengthwise movement into and out of the path of said container.

In testimony whereof, I affix my signature
30 hereto.

EDGAR W. VAHLE.
